SAFETY RAZOR

Earl B. Hoff, Cleveland Heights, Ohio

Application June 13, 1930. Serial No. 460,995

7 Claims. (Cl. 30—12)

This invention relates to a safety razor and particularly to a safety razor of the double edge blade type.

An object of the invention is to provide a safety razor wherein the outer and inner guard members may be substantially separated so as to allow the blade to be moved back for insertion in a stropping device without removing the blade from the razor.

10 An additional object is to provide a safety razor wherein the outer and inner guard members may be substantially separated without increasing the length of the razor.

15 A further object is to provide a safety razor wherein the razor blade may be changed by unscrewing one part only of the razor.

20 A still further object is to provide a safety razor wherein the blade tension is adjustable and means arranged on the razor for indicating the different adjustments of the blade.

25 A further object is to provide a safety razor which is so constructed that when the guards are separated to allow the razor blade to be inserted in a stropping device the blade will be held against rotation.

30 Another object is to provide a safety razor which is so constructed that the razor may be easily cleaned and in addition is formed of a minimum number of parts.

35 Additional objects and advantages will become apparent hereinafter as the detailed descriptions of several embodiments of the invention proceed.

Several embodiments are illustrated in the accompanying drawing wherein;

35 Figure 1 is a view of one form of razor, the same being shown partly in side elevation and partly in section;

40 Fig. 2 shows in side elevation the parts of the razor disclosed in Fig. 1, the said parts being separated and arranged in position for assembling;

45 Fig. 3 is a view taken substantially on line 3—3 of Fig. 1 looking in the direction of the arrows;

Fig. 4 is a longitudinal sectional view of the 50 razor shown in Fig. 1, but taken 180° from the position of the razor in Fig. 1;

Fig. 5 is a view similar to Fig. 4, but showing a modified form of razor;

55 Fig. 6 shows in plan a razor blade suitable for use with the razor shown in Fig. 1;

Fig. 7 is a plan view of the razor blade suitable for use with the razor shown in Fig. 5;

Fig. 8 is a detail view partly in section and 60 partly in elevation of a modified form of inner guard member, the section being taken along the line 8—8 of Fig. 9;

Fig. 9 is a sectional view taken on line 9—9 of Fig. 8 looking in the direction of the arrows; and

65 Fig. 10 is a perspective view of the razor with

the inner guard moved rearward and the blade positioned ready for insertion in the stropper.

The razor shown in Figs. 1 to 4 inclusive includes an outer guard member 10 which is curved transversely of its longitudinal length so as to 65 have its inner side concave. As is usual in razors of this type the inner side of the outer guard member 10 is provided with a pair of spaced inwardly extending projections 11 arranged on the longitudinal center line of the member 10 and on the opposite sides of the middle point of such line. The member 10 is further provided with a rearwardly extending shaft 12 projecting from the inner side of the member at the middle point thereof and provided for a portion of its length 70 with outwardly extending diametrically opposed splines or ribs 13. The rear end of the shaft 12 beyond the splines or ribs 13 is threaded as indicated at 14.

The inner guard member 15 is curved transversely of its longitudinal length in the same manner as the outer guard member 10 so that the two members may be brought together in complementary relationship to clamp a razor blade therebetween. The inner guard member 15 is substantially of the same size as the outer guard member 10 with the exception that the guard teeth 16 provided on each longitudinal edge of the member 15 extend outwardly beyond the longitudinal edges of the guard member 10. 80 The inner guard member 15 is provided with a pair of openings 17 so arranged that when the two guard members are in cooperating clamping position the projections 11 on the outer guard member will extend through the openings 17 of the inner guard member. The inner guard member 15 is further provided at the middle thereof with an opening 18 of generally circular configuration except that it is provided with diametrically opposed slots 19, whereby the opening 18 and the slots 19 are of the same configuration as the shaft 12 and the ribs or splines 13 for the purpose of allowing the inner guard member 15 to be positioned upon the shaft 12 and held 85 against rotation thereon.

100 A tube 20 is integral with and extends rearwardly from the concave side of the guard member 15, this tube being concentrically arranged with respect to the opening 18 and of a diameter substantially equal to the combined length of the grooves 19 and the diameter of the opening 18, so that the shaft 12 and splines or ribs 13 may have sliding movement in the tube.

110 The length of the tube 20 is such that it does not extend beyond the end of the shaft 12 when the outer and inner guard members are in clamping position, in fact, the rear end of the tube terminates a substantial distance inwardly of the 115

120

end of the shaft 12 when the parts are in the position mentioned.

The handle of the razor, indicated at 21, is preferably cylindrical in shape and of such diameter that the tube 20 may slide or telescope freely thereon. The handle 21 is provided with a knurled knob or head 22 at one end and with an exteriorly threaded portion 23 at its opposite end, while extending inwardly of the handle 10 from this last mentioned end is a recess or bore 24 threaded for a portion of its length as indicated at 25. A knurled nut 26 is arranged on the handle 21 and is adapted to co-operate with the threaded portion 23 thereof for a purpose 15 later to be explained and made apparent.

In Fig. 6 of the drawing a razor blade 27 of the double edge type is shown, such blade being particularly adapted for use with the razor shown in Figs. 1 to 4 inclusive, although it should be 20 understood that other forms of blades could be used therein. The blade 27 is provided with openings 28 through which the projections 11 on the outer guard member 10 may extend, while the center of the blade 27 is provided with an 25 opening 29 having a pair of diametrically opposed grooves 30 to enable the blade to be positioned over the shaft 12 with the splines 13 of the shaft engaging in the grooves 30 of the blade to hold the blade against rotation on the shaft. 30 Although a pair of grooves 30 are disclosed in the razor blade it is perfectly apparent that three or more of such grooves might be provided therein (see Fig. 7) or the grooves 30 might be extended to communicate with the openings 28 35 of the blade.

The operation of the razor disclosed in Figs. 1 to 4 inclusive is as follows:

The inner guard 15 is separated from the outer guard, as shown in Fig. 2, and the blade 27 is 40 then positioned on the shaft 12 with the shaft 12 extending through the opening 29 of the blade and the splines or ribs 13 of the shaft extending through the grooves 30 adjacent the openings 29 in the blade. The blade may then be moved 45 toward the outer guard member 10 until the projections 11 extend through the openings 28 in the blade.

The shaft 12 is then passed through the opening 18 in the inner guard member and as the 50 inner guard member is moved toward the outer guard member the splines 13 will pass through the grooves 19 of the member 15 thus permitting the inner guard member to move toward the outer guard member to clamp the blade 27 therebetween, in which position the shaft 12 and splines 13 will be within the tube 20, the threaded end 14 of the shaft extending rearwardly a substantial distance beyond the end of the tube.

The handle 21 may then be screwed down upon the threaded end 14 of the shaft, after which the knurled nut 26 on the handle 21 can be screwed down upon the threaded portion 23 of the handle so as to press against the rear end of the tube 20 and thereby move the inner guard member 15 into clamping position with the outer guard member 10.

It will be seen that the nut 26 may be adjusted to vary the tension imposed upon the blade 27 by the inner guard member 15, graduations 31 being arranged on the tube 20 adjacent its rear end to co-operate with a mark 32 on the nut 26 to indicate the adjustment of the blade tension.

It will further be seen that when the nut 26 is unscrewed from the threaded portion 23 and moved back on the handle 21, the inner guard

member 15 and the tube 20 may be slid rearwardly over the handle to thus substantially separate the guard members and expose the blade, so that it can be inserted in a stropping device, it being noted that the blade does not have to be removed from the razor for this purpose and that the rearward movement of the inner guard 80 15 and tube 20 does not increase the length of the razor. Of course, the guard members may be separated in the same manner when it is desired to clean the razor. In Fig. 10 I have shown the position of the parts of the razor when the latter is to be inserted in the stropper. To thus position the parts, it is only necessary to unscrew the nut 26 and slide it back onto the unthreaded portion of the handle 21 and then slide the inner guard member back to the position illustrated and place the blade on the shaft 12 about midway between the guard members. This effects no change in the overall length of the razor. A 85 90 stropper which is adapted to receive the razor with the parts thus positioned is described and claimed in a companion application filed by me of even date herewith.

A slightly modified form of razor is disclosed in Fig. 5, the outer guard member being indicated at 33 and of substantially the same construction as the guard member 10 in the form just above described; however, the guard member 33 is provided with a rearwardly extending shaft 34 similar to the shaft 12 of the other form of razor, but preferably of reduced diameter and of substantially greater length. The shaft 34 is provided with one or more splines or ribs 35 (four of these ribs or splines being shown in the drawing by way of illustration) while the rear end of the shaft 34 is reduced in diameter and threaded as indicated at 36.

The inner guard member 37 is substantially the same as the inner guard member 15, it being noted however, that the rearwardly extending tube 38 is of relatively less diameter than the diameter of the tube 20 and is provided adjacent its rear end with an exteriorly threaded portion 39.

The handle 40 is substantially tubular and of such size that it will telescopically receive the tube 38 when the inner guard member 37 is moved rearwardly away from the outer guard member 33. The rear end of the handle 40 is closed by a solid plug-like portion 41 provided on its inner side with a threaded centrally arranged recess 42 into which the threaded end 36 of the handle 34 may be screwed. A nut 43 is arranged on the tube 38 and is adapted to be screwed upon the threaded portion 39 of the tube.

In assembling this form of razor the inner guard member 37 is positioned upon the shaft 34 in substantially the same way as the inner guard member in the other form. The handle 40 may then be positioned over the shaft 34 and the threaded end of the shaft screwed into the recess 42 in the plug-like portion 41 of the handle. After the parts have been thus assembled the nut 43 is screwed upon the threaded portion 39 of the tube 38 with the result that the nut engaging the inner end of the handle forces the tube 38 and the inner guard member 37 toward the outer guard member 33 so as to clamp the blade therebetween. When it is desired to separate the guard members to clean the razor or to strop the blade it is merely necessary to loosen the nut 43 and then to slide the tube 38 rearwardly within the handle 40.

In Fig. 7 the blade 27 is of the same general construction as the blade 27 shown in Fig. 6, it 150

being noted however, that the central opening 44 is smaller than the opening 29 and is provided with four grooves 45, the purpose of the reduced opening 44 and the grooves 45 being to permit the blade to be positioned upon the shaft 34.

In Figs. 8 and 9 a modified form of inner guard member 46 is disclosed. The difference in this form of guard member over the guard members 10 15 and 37 previously described resides in the construction of the guard teeth, it being noted that the guard member 46 is provided with cutout portions 47 extending longitudinally of the guard and inwardly of the guard teeth. Another difference existing in the guard teeth disclosed in the modified form is that the teeth are in the form of a roller made up of a plurality of disc members 48 arranged in spaced relation on a supporting rod or shaft 49. The purpose of this form 20 of inner guard member is to facilitate the passage of the lather and bristles through the inner guard to prevent clogging of the razor while the series of disc members 48 form a smoother face-engaging surface than do the teeth of the inner 25 guards 15 and 37.

Although several preferred embodiments of the invention have been disclosed herein, it should be understood that the invention is susceptible of such modifications and adaptations as fall within 30 the scope of the appended claims.

Having thus described my invention, I claim:

1. A safety razor comprising a handle, an outer guard member having a shaft to the end of which said handle is connected and upon which 35 a razor blade is adapted to be directly engaged and slidably supported, an inner guard member movably supported upon said shaft and having a tubular portion likewise supported upon and in contact with said shaft whereby said inner guard 40 member may be substantially separated with respect to the outer guard member, and means cooperating with said handle and said tubular portion of the inner guard member for holding the guard members in blade clamping relationship.

45 2. A safety razor comprising a substantially cylindrical handle, an outer guard member having a shaft to the end of which said handle is connected and upon which a razor blade is adapted to be directly engaged and slidably supported, an inner guard member movably supported upon 50 said shaft and having a tubular portion likewise supported upon and in contact with said shaft, whereby said inner guard member may be substantially separated with respect to the outer 55 guard member with the tubular portion thereof telescoping over the cylindrical handle, and means cooperating with said handle and said tubular portion of the inner guard member for holding the guard members in blade clamping 60 relationship.

65 3. A safety razor of the double edge blade type comprising an outer guard member, a shaft extending from the said member and provided with radially projecting ribs for a portion of its length and having its outer end threaded, an inner guard member having a tubular portion extending from one side thereof, said inner guard member having an opening complementary to the ribbed portion of said shaft and aligned with the 70 said tubular portion, whereby said inner guard member and tubular portion may be slidably, but non-rotatably supported upon said shaft, a han-

dle secured to the threaded end of said shaft, said handle having its inner end threaded, and a nut on said threaded end of the handle adapted to engage the adjacent end of said tubular portion to maintain the inner guard member in blade clamping relationship with said outer guard member.

80 4. A safety razor of the double edge blade type comprising an outer guard member, a shaft extending from said member, an inner guard member having a tubular portion extending from one side thereof, said inner guard member and tubular portion being slidably supported upon said shaft, a tubular handle of larger diameter than said tubular portion arranged over the end of said shaft and secured thereto, said tubular portion of the inner guard member being adapted to telescope within said handle when the guard members are separated, and means on said tubular portion for engaging the adjacent end of said tubular handle to maintain the inner guard member in blade clamping relationship with said outer guard members.

85 5. A safety razor comprising an outer guard member having a shaft extending therefrom, an inner guard member having a tubular portion extending therefrom of less length than said shaft, said inner guard member and tubular portion thereof being slidably supported upon said shaft, a handle secured to the end of said shaft 100 with its inner end adjacent to the end of said tubular portion when the inner guard member is in clamping relationship with respect to the outer guard member, said handle and said tubular portion being telescopically interfitting, and means for maintaining said guard members in 105 clamping relationship.

110 6. A safety razor comprising an outer guard member having a shaft extending therefrom, an inner guard member having a tubular portion extending therefrom of less length than said shaft, said inner guard member and tubular portion thereof being slidably supported upon said shaft, a handle secured to the end of said shaft with its inner end adjacent to the outer end of said tubular 115 portion when the inner guard member is in clamping relationship with respect to the outer guard member, said handle being adapted to telescope within said tubular portion when the guard members are separated, and means on said 120 handle for engaging the adjacent end of said tubular portion to maintain the guard members in 125 clamping relationship.

130 7. A safety razor comprising an outer guard member having a shaft extending therefrom, said shaft being of irregular cross-sectional configuration for a portion of its length, an inner guard member having an opening therein complementary to the irregular cross-sectional configuration of the shaft and a tubular portion aligning with 135 said opening and extending rearwardly therefrom and of less length than said shaft, said inner guard member and tubular portion thereof being slidably supported upon said shaft, a handle secured to the end of said shaft with its inner end adjacent to the outer end of said tubular portion when the guard members are in 140 clamping relationship, said tubular portion and said handle being telescopically interfitting, and means for maintaining said guard members in 145 clamping relationship.

EARL B. HOFF.
